UNITED STATES PATENT OFFICE.

SYRUS C. DUNN, OF MARION, ARKANSAS.

DREDGING APPARATUS.

Application filed August 2, 1927. Serial No. 210,399.

This invention relates to a dredging apparatus for river beds and comprises a plurality of river bed digging blades rotatably mounted on a shaft and operated through a 5 drag wheel adapted to travel over the river bed and carried by a boat arranged on the surface of the water whereby upon the movement of the boat the digging blades will loosen the sediments formed on the bed of 10 the river so that the same may be conveyed downstream by the river current.

A further object is to arrange hoisting means on the boat and attachable to the drag wheel and shaft carrying the diggers where- 15 by to raise or lower the same out of engagement with the river bed when so desired or to permit the adjustment thereof for digging operations at varying depths.

A further object is to attach a drag to the 20 frame supporting the digger blades and drag wheel and adapted to engage obstacles or some obstruction in the river bed for the purpose of removing the same therefrom.

A further object is to provide a device of 25 this character of simple and practical construction, strong and durable, efficient and reliable in performance, relatively inexpensive to manufacture and install upon a conventional type of boat, and otherwise well 30 adapted to the purpose for which the same is intended.

Other objects and advantages reside in the 35 special construction and combination of the various elements forming the invention, with reference to the accompanying drawings, wherein:—

Figure 1 is a side elevational view of one 40 end of a boat showing the apparatus in operative position for dredging a river bed.

Figure 2 is a perspective view of the drag wheel hoisting hook.

Figure 3 is a similar view of the axle for the drag wheels.

Figure 4 is a top plan view of the app- 45 paratus.

Figure 5 is a transverse sectional view through the digging blade shaft showing one set of such blades in elevation carried thereon, and,

Figure 6 is a fragmentary sectional view 50 through the drag wheel showing the manner of attaching the gear thereto.

Referring now to the drawing in detail, wherein for the purpose of illustration I 55 have disclosed a preferred embodiment of my invention, I provide a boat indicated at

5 of any suitable construction adapted to float upon the surface of a river or other stream, at one end of which is secured a pair of bearing brackets 6 adapted to secure a 60 transversely extending rod 7 to the boat, with each end of the rod extending outwardly at opposite sides of the boat and arranged to be inserted in one of the openings 8 formed in a pair of shaft members 9 which are piv- 65 otally carried on the ends of said rod and extending outwardly beyond the end of the boat with the outer ends thereof connected by an axle 10 at each end of which is rotatably mounted a drag wheel 11 arranged to 70 travel along the river bed.

At one side of each of the wheels 11 is secured a bull gear 12, suitably secured to the spokes of the wheel by U-bolts 13 and engaging smaller spur gears 14 mounted on 75 opposite ends of a square shaped shaft 15, the ends 16 of said shaft being journaled in openings formed in supports 17 pivotally carried on the axle 10.

At spaced intervals along the shaft 15 I 80 provide a plurality of sets of digger blades 18, said blades being carried at the ends of arcuate shaped arms 19 extending radially from the shaft and having the ends of the arms carrying the blades extending in a di- 85 rection of movement of the boat.

On the outer end of the axle 10 I pivotally attach one end of supporting arms 20 with the opposite ends thereof supporting a transversely disposed rod 21 upon which is ar- 90 ranged a plurality of drag teeth 22 at spaced intervals thereon and arranged to be dragged along the bed of the river for engagement with submerged objects so as to remove the same therefrom.

The shaft 21 is adapted to be engaged by a pair of hooks 23 secured at the ends of a transversely disposed hoisting arm 24 to which is attached a cable 25 extending upwardly over a drum 26 mounted upon a 100 frame 27 arranged on the deck of the boat.

A crank 28 is attached to the drum where- 105 by to hoist the cable 25 upwardly and thus raise the drag 22 from the river bed.

Hoisting hooks similar in construction to that provided for attaching to the drag rod 21 are also provided for attaching to the digger blade shaft 15 and the drag wheel axle 10 and having cables 29 and 30 attached respectively thereto for winding upon sepa- 110 rate drums 31 and 32 respectively by cranks 33 and 34. In this manner, the drag rod

21, the digging blade shaft 15 and the drag wheel axle 10 may be separately adjusted at different elevated positions.

In the operation of the device, as the boat 5 travels along the surface of the water, the dredging apparatus is lowered therefrom until the drag wheels 11 engage the bed of the stream thereby causing the rotation thereof and by reason of the connection of 10 the digger blade shaft 15 through the gears 12 and 14 the shaft 15 will thus be rotated in a direction opposite from the wheel so as to cause the blades to dig into the river bed in a direction opposite to the travel of the boat and thus form a positive means of 15 loosening the sediment therefrom. The same is then permitted to be carried downstream through the action of the current of the water.

20 Any submerged obstruction lying along the river bed will be engaged by the drags 22 and hoisted to the deck of the boat for removal.

It is obvious that my invention is susceptible to various changes in the construction thereof, without departing from the spirit or scope of the invention as herein-after claimed or sacrificing any of its advantages, and I accordingly claim all such 25 forms of the device to which I am entitled.

I claim:—

1. In a river bed dredging apparatus, a boat having a pair of shafts pivotally attached at opposite sides thereof, an axle car-

ried at one end of the shaft, wheels rotatably mounted on the axle, gears connected to said wheels, a rotatable shaft, shaft supports connecting the same with said axle, gears carried by the shaft operatively engaged with the first named gears, a plurality of 40 digger blades carried by said shaft, digging elements carried thereon and extending in a direction opposite to the movement of the boat, a drag rod having a plurality of drag elements attached thereto, supporting rods 45 for said drag rod pivotally attaching the same to the wheel axle, and cables attached to the drag rod, to the shaft, and to the axle and selectively operable from the boat whereby to vertically adjust the same. 50

2. A water bed dredging apparatus comprising supporting means movable on the surface of the water, a pair of rotating elements including a bed engaging element operable upon the movement of the supporting means and a bed digging element operatively connected to said first named element, a supporting frame for said first named element adjustably attached to the supporting means, a rake pivotally carried by said supporting frame and disposed rearwardly of the rotating element and means 55 operable from the supporting means for selectively adjusting said rotating elements and said rake vertically. 60

In testimony whereof, I affix my signature.

SYRUS C. DUNN.
